UNITED STATES PATENT OFFICE.

JOHN CLAYTON BACKUS, OF SMETHPORT, PENNSYLVANIA.

UMBRELLA RACK.

Application filed December 12, 1923. Serial No. 680,253.

This invention relates to an improved umbrella rack particularly designed to accommodate one or more check locks for locking umbrellas upon the rack and seeks, among other objects, to provide a rack which may be economically produced entirely from sheet metal.

The invention seeks, as a further object, to provide a rack so constructed that a number of the racks may be readily assembled in a banked unit.

The invention seeks, as a still further object, to provide a rack so constructed that an umbrella may be readily placed therein without liability of snagging the umbrella cover and which, should the umbrella be unfolded, will serve to bunch and retain the ribs of the umbrella in close relation so as to prevent catching of the ribs upon the rack as well as the interference of one umbrella with another.

And the invention seeks, as a still further object, to provide a rack embodying a drip pan semi-permanently mounted so that while the drip pan cannot become accidentally displaced and lost, the pan may, nevertheless, be removed and renewed and wherein the pan will be equipped with a spout so that water may be drawn off from the pan without disturbing umbrellas in the rack.

Other and incidental objects will appear hereinafter.

In the drawings:

Figure 1 is a perspective view of my improved umbrella rack.

Figure 2 is a vertical sectional view taken medially through the device.

Figure 3 is a detail perspective view showing the lock supporting plate of the rack,

Figure 4 is a detail sectional view on the line 4-4 of Figure 2, looking in the direction of the arrows, this view particularly showing the drip pan employed as well as the rest irons for the legs of the rack, and

Figure 5 is a side elevation showing a rack unit composed of a pair of the racks.

As previously intimated, the rack of the present invention is formed entirely of resilient sheet metal and in carrying the invention into effect, I employ a pair of identical side plates 10 which are arranged in vertical parallel relation and are formed at their vertical edges with flanges 11. Extending between the side plates at their lower ends is a channel shaped bottom plate 12

having depending side flanges 13 riveted to the flanges 11 and end flanges 14 abutting the lower margins of the side plates. Accommodated between the flanges 13 of the bottom plate to overlie the end flanges 14 of said plate, are angle shaped rest plates 15 connected with the side plates 10 by rivets or other suitable fastening devices extending through the vertical flanges of the rest plates and through the end flanges 14 of the bottom plate. As brought out in detail in Figure 4 of the drawings, the horizontal flanges of the rest plates are disposed to project away from the side plates 10 toward each other and bolted or otherwise detachably secured to said rest plates are legs 16. These legs are preferably formed of suitable metal bars bent downwardly and inwardly near their ends to form feet 17.

Extending between the side plates 10 at their upper ends is a lock supporting top plate 18 having a narrow depending front flange 19 and a wide back flange 20 riveted to the rearmost side flanges of the side plates 10, as well as end flanges 21 also riveted to said side plates. The plate 18 is of less width than the side plates 10 and is, as best shown in Figure 1, designed to support a bank of individual check locks, as indicated at 22. These locks are each detachably secured to the plate 18 and are preferably of the general type illustrated in Patent No. 913,188, granted to me February 23, 1909. However, since the specific structure of the lock forms no part of the present invention, it is unnecessary to herein describe said locks in detail. Nevertheless, in the interest of clarity, it may be stated that the casing of each of the locks is provided with a cavity or slot 23 to freely accommodate the handle portion of an umbrella and a lock bolt is provided to project across said slot for limiting the umbrella against displacement, the bolt being controlled by a key check 24.

Resting upon the bottom plate 12 is an oblong drip pan 25 somewhat less in length than the distance between the side plates 10. The side and bottom walls of the pan are preferably fashioned of a single piece of material while the end walls are formed separately and provided with flanges soldered or otherwise secured to the side and bottom walls. Set into the front side wall of the pan is an outlet spout 26 which may be normally closed by a suitable stopper 27.

and rising from the end walls of the pan are reduced laterally inclined wings 28 yieldably bearing at their upper ends against the side plates 10, the wings being compressed 5 between the sides. Thus these wings will serve to center the drip pan between the side plates and yieldably hold the pan against endwise movement as well as prevent rattling. Riveted to the rearmost flanges 11 is 10 a retaining plate 29 provided at its upper edge with an inturned longitudinal lip 30 engaging over the upper edge of the rear side wall of the drip pan; and detachably connected to the front flanges 11 of said 15 side plates is a similar retaining plate 31 having a longitudinal inturned lip 32 engaging over the upper edge of the forward side wall of the pan. The plate 31 is detachably connected with the front side 20 flanges of the side plates 10 by screws or other suitable fastening devices 33 so that while said plate may be readily removed for displacing the pan, still the pan will be more or less permanently secured in position. 25 Extending between the side plates 10 above the drip pan is a gathering plate 34 having depending side flanges 34' riveted to the side flanges 11 of said side plates, and formed through the plate 34 are spaced circular openings 35 each adapted to receive an umbrella therethrough. As shown in detail in Figure 4, the edge of each of the openings is rolled downwardly and laterally under the plate so that a smooth surface will be 30 presented to an umbrella cover and possible snagging of the cover thus avoided. Extending between the gathering plate 34 and the drip pan 25 is a scuff plate 36 abutting the rear side flange of said gathering plate 40 and detachably secured to the rear side flanges of the side plates 10 by screw bolts or other suitable fastening devices 37. At its lower end portion, the plate is tapered to extend into the drip pan so that when an 45 umbrella is inserted through one of the openings 35 of the gathering plate, the point of the umbrella will strike the scuff plate to be directed by the scuff plate into the drip pan when the handle portion of the umbrella 50 may be moved into the slot 23 of the alining lock 22 and secured by said lock. In this connection, it will be noted that when an umbrella is thus inserted through one of the 55 openings 35, the ribs as well as the cover of the umbrella will be gathered and bunched together by the wall of said opening so that even though the rib structure of the umbrella is unfastened when folded, the umbrella will, nevertheless, be held against 60 opening movement. Extending between the rear flanges 11 of the side plates 10 above the plate 34 is a cross strip 38 upon which are mounted spaced channeled pegs 39 provided at their inner ends with lugs 40 inserted 65 through the strip and overturned there-

against for connecting the pegs with the strip. The pegs are located in planes passing between the openings 35 of the gathering plate 34 so that said pegs will serve to separate umbrellas inserted through said 70 openings. Extending between the rear flanges 11 of the side plates 10 above the strip 38 is a stop strip 41. This strip is located to cooperate with the upper end portions of the ribs of an umbrella placed in 75 the rack for confining said ribs within the lines of the rack and preventing the protrusion of the upper ends of the ribs at the rear of the rack to possibly become caught thereagainst when the umbrella is removed. 80

In Figure 5 of the drawings, I have shown a pair of the racks banked to form a unit. For this purpose I provide a pair of legs 42 similar to the legs 16 but bent to define stepped horizontal portions 43 accommodating the rest plates 15 of the racks and extending through said rest plates and through said portions of the legs are bolts or other suitable fastening devices 44 connecting the racks with the legs. Furthermore, in order 85 that the racks may be banked, I provide the side plates 10 of each rack with vertically spaced pairs of openings 45 and extending transversely between the racks at the sides thereof are tie straps 46 secured to the racks 90 by bolts or other suitable fastening devices 47 accommodated by the upper pairs of openings of one rack and the lower pairs of openings of the other rack. The racks are thus securely connected with each other to 95 form a rigid unit and while I have shown a unit embodying only two of the racks, still, as will be appreciated, a unit embodying three or more of the racks may be readily produced by simply elongating the legs 42 100 to embody the desired number of steps therein.

Having thus described the invention, what is claimed as new is:

1. In a sheet metal structure including 110 spaced vertical plates, a bottom plate having depending marginal flanges at its four edges, and angle rest plates disposed between the side flanges of the bottom plate, with the vertical flange against the depending end 115 flange thereof, and with the horizontal flange spaced from the bottom plate, the vertical flanges of the bottom and rest plates being secured to each other and to the lower portions of the vertical plates. 120

2. In a sheet metal structure including 125 spaced vertical plates having inturned flanges at their vertical edges, a bottom plate having depending marginal flanges at its four edges and having the depending side flanges secured to the inturned flanges of the vertical plates, and angle rest plates disposed between the side flanges of the bottom plate, with the vertical flange against the depending end flange thereof, and with the 130

horizontal flange spaced from the bottom plate, the vertical flanges of the bottom and rest plates being secured to each other and to the lower portions of the vertical plates.

- 5 3. In a sheet metal structure including spaced vertical plates having inturned flanges at their vertical edges, a bottom plate having depending marginal flanges at its four edges and having the depending side flanges secured to the inturned flanges of the vertical plates, and angle rest plates disposed between the side flanges of the bottom plate, with the vertical flange against the depending end flanges thereof, and with the horizontal flange spaced from the bottom plate, the vertical flanges of the bottom and rest plates being secured to each other and to the lower portions of the vertical plates, and metal strips underlapping the rest plates
- 10 15 20
- and secured to the horizontal flanges thereof and extended outwardly and downwardly to provide feet.

4. In a sheet metal structure including spaced vertical plates having inturned flanges at their vertical edges, a bottom plate having depending marginal flanges at its four edges arranged between the vertical plates and the inturned flanges thereof and secured thereto, and a top plate having depending side and end flanges, the rear flange being secured to the inturned flanges of the vertical plates and the end flanges being secured against the inner sides of the said vertical plates.

- 35 5. In a sheet metal structure including spaced vertical plates having inturned flanges at their vertical edges, a bottom plate having depending marginal flanges at its four edges arranged between the vertical plates and the inturned flanges thereof and secured thereto, a drip pan on the bottom plate and having flared end wings engaging the vertical plates, and retaining plates secured to the inturned flanges of the vertical plates and having inner flanges along their

top edges to engage over the front and rear walls of the drip pan.

6. In a sheet metal structure including spaced vertical plates having inturned flanges at their vertical edges, a bottom plate having depending marginal flanges at its four edges arranged between the vertical plates and the inturned flanges thereof and secured thereto, a drip pan on the bottom plate and having flared end wings engaging the vertical plates, retaining plates secured to the inturned flanges of the vertical plates and having inner flanges along their top edges to engage over the front and rear walls of the drip pan, and a scuff plate secured to the rear inturned flanges of the vertical plates and extending into the drip pan and overlapping the rear wall of the rear retaining plate.

7. In a sheet metal structure including spaced vertical plates having inturned flanges at their vertical edges, a bottom plate having depending marginal flanges at its four edges arranged between the vertical plates and the inturned flanges thereof and secured thereto, a drip pan on the bottom plate and having flared end wings engaging the vertical plates, retaining plates secured to the inturned flanges of the vertical plates and having inner flanges along their top edges to engage over the front and rear walls of the drip pan, a scuff plate secured to the rear inturned flanges of the vertical plates and extending into the drip pan and overlapping the rear wall of the rear retaining plate, and a gathering plate having depending front and rear flanges secured to the inturned flanges of the vertical plates, and having the rear flange abutting the top edge of the scuff plate, the gathering plate being formed with article-receiving openings.

In testimony whereof I affix my signature.

JOHN CLAYTON BACKUS.
